UNITED STATES PATENT OFFICE

WILLIAM E. BOCK, OF TOLEDO, OHIO, ASSIGNOR TO THE BOCK LAUNDRY MACHINE COMPANY, OF TOLEDO, OHIO, A CORPORATION OF OHIO

DESIGN FOR A LAUNDRY-MACHINE CASING

Application filed August 18, 1930. Serial No. 36,692. Term of patent 3½ years.

To all whom it may concern:

Be it known that I, WILLIAM E. BOCK, a citizen of the United States of America, residing at Toledo, in the county of Lucas and State of Ohio, have invented a new, original, and ornamental Design for Laundry-Machine Casing, of which the following is a specification, reference being had therein to the accompanying drawing, forming part

thereof, in which the figure is a perspective view of a laundry machine casing showing my new design.

I claim:

The ornamental design for a laundry machine casing substantially as shown.

In testimony whereof I affix my signature.

WILLIAM E. BOCK.
